UNITED STATES PATENT OFFICE

WALLACE C. MILLS, OF ROCKFORD, ILLINOIS, ASSIGNOR TO J. L. CLARK MANUFACTURING CO., OF ROCKFORD, ILLINOIS, A CORPORATION OF ILLINOIS

SPOOL

Application filed July 7, 1928. Serial No. 291,074.

The invention has reference to spools of the type comprising a tubular core with substantially flat sheet metal heads secured upon opposite ends of the core. The core of such a spool is commonly made from a flat sheet of metal, and in fastening the heads onto the ends of the core the joint formed between the meeting edges of the sheet constituting the core are apt to present sharp cutting edges. These are objectionable especially in the case of a spool used for adhesive tape, it being customary to hold the spool between the thumb and forefinger or to insert, in the case of larger spools, a thumb into the end of the core during the operation of removing tape from the spool.

The object of this invention is to provide, through the use of a separately formed connecting member between each head and the core, an improved construction for rigidly securing the head onto the core while at the same time presenting a smooth uninterrupted surface at the end of the core.

A further object is to provide a construction for the spool rendering it possible to manufacture the same on an economical basis.

The foregoing objects, together with other and ancillary advantages are attained by the construction and arrangement shown in the accompanying drawings forming part hereof, it being contemplated however, that various changes may be made by those skilled in the art without departing from the spirit and scope of the invention.

In the drawings:

Figure 1 is a side elevation of a spool of the character referred to.

Fig. 2 is a central vertical sectional view through one end of the spool showing the parts assembled, but before the forming or interlocking operation.

Fig. 3 is a similar view on a larger scale but with the parts fastened together.

Fig. 4 is a similar view of a modified form.

The spool comprises a tubular body or core 7 having heads 8 fastened on opposite ends of the core. The core is preferably formed 50 from a flat sheet of metal rolled into tubular

form, the opposite ends of the sheet meeting at 9.

Each head 8 is formed from a sheet of metal centrally apertured so as to form a flat ring or disk the outer peripheral edge of which may be curled as at 10 for finishing and strengthening purposes. The heads are customarily lithographed for purposes of identifying the manufacturer or to convey any other desired information, this being done before the heads are assembled onto the ends of the core.

Near each end the core is shaped to provide an outwardly extending bead 11 leaving an end portion 12 projecting beyond the bead. 65 Fitting snugly over the end portion is a U-shaped part of an annulus 13 formed from a flat sheet of metal and having prior to assembly an inner peripheral leg 14 and an outer peripheral leg 15. The inner leg preferably extends inwardly into the core beyond the bead 11 and the outer leg preferably terminates just short of the bead and has, in the present instance, formed thereon an out-turned flange 16.

Each of the spool heads 8 has an internal diameter such as to fit rather snugly about the annulus 13, and more specifically about the outer peripheral leg thereof, and in the initial assembly of the parts the head is arranged to seat upon the outturned flange 16.

With the parts thus assembled (Fig. 2) the fastening of the heads onto the ends of the core is accomplished by bending each annulus together with the end portion 12 therein, outwardly flat upon the head 8, as shown in Fig. 3, while at the same time compressing the parts longitudinally of the axis of the core so as to flatten the bead and securely clamp the parts together.

It will be observed from Fig. 3 that by the construction provided an outwardly opening groove is formed between the flange 16 and the peripheral leg 15 of the annulus, in which the inner peripheral edge of the head is securely clamped. Similarly the end portion 12 of the core becomes bent to form an outwardly opening groove to receive the outer leg of the annulus doubled upon itself, with the head therebetween as above set 10v

forth. Thus the annulus is not only utilized in the fastening of the head onto the core, but it serves to cover the joint 9 formed between the meeting edges of the sheet from which the core is made.

5 By interlocking each head and core together through the medium of the annulus, all danger of stressing, breaking or otherwise injuring the metal of the head and of the annulus is avoided. This is especially important from the standpoint of economy in manufacture in that it enables the use of ordinary commercial stock sheet metal, simplifies the assembling and forming operation, reduces the amount of scrap produced, insures against distorting the printed or lithographed surfaces of the heads, and avoids the necessity for using a lubricant on the dies where an excessive amount of stressing must occur, it being necessary subsequently to remove such lubricant.

10 If desired the heads may in the forming operation be offset as at 17 (Fig. 3) to receive the flattened bead 11, the inner face of the latter being substantially flush with the inner face of the head.

15 As shown in Fig. 4, the annulus may in the case of some spools have formed integral therewith an end wall 18. This wall in the present instance is shown connected to the inner leg 14 of the annulus by an inturned portion 19 and the end wall is disposed substantially in the plane of the curl 10 at the edge of the head 8. The wall 18 is centrally apertured to receive an inner tubular member 20 the ends of which are flanged outwardly as at 21 so as to engage with the edges of the aperture in the wall. This permits the mounting of the spools when desired on suitable pivotal supports and the portion of the end walls in the plane of the head is desirable in that it permits of the use of short end pivots which offer very little obstruction to the placing of the spool on the pivots.

20 45 I claim as my invention:

1. A spool comprising a core formed from a flat sheet of metal and bent into tubular form, heads at opposite ends of the core, each end of the core being constructed to form a shoulder and an end portion projecting from the shoulder, an annulus having a U-shaped portion fitting snugly over said end portion, said head comprising a centrally apertured disk encircling the annulus and held by said shoulder against movement inwardly of the core, and the end portion of the core together with said U-shaped portion of the annulus being bent outwardly with one leg of said U-shaped portion bearing directly on said disk.

2. A spool comprising a core, an annulus having a portion U-shaped in form and fitting over one end of the core with an inner leg extended into the core and an outer leg having an outturned flange, and a head in the

form of a disk centrally apertured and resting upon said flange, said U-shaped portion of the annulus together with the end of the core being bent outwardly upon said head to clamp it against said flange.

3. A metallic spool comprising a core formed from a flat sheet of metal, an annulus having a portion U-shaped in form and fitting over one end of the core, said core having a bead thereon near said end, and said U-shaped portion having a flange adjacent said bead, and a head comprising a disk centrally apertured and adapted to rest upon said flange, said U-shaped portion of the annulus together with the end portion of the core therein being bent outwardly upon said head so as to clamp the same together with said flange upon said bead.

4. A spool formed of sheet metal and comprising a core, a head, and an annulus interlocked with the head and the core, said core being bent to provide an outwardly opening groove to receive a portion of the annulus, and said portion of the annulus in turn being shaped to provide an outwardly opening groove to receive the inner peripheral edge of the head.

5. A spool comprising a core, a head, and an annulus interlocked with the head and the core, said annulus having a part bent to form an inwardly opening groove to receive the end portion of the core and an outwardly opening groove to receive the inner peripheral edge of the head.

6. A spool having a core, a head on one end of the core, and an annulus connecting the head to the core, said annulus having a portion U-shaped in form so as to provide a channel adapted to receive snugly the end of the core, said head having a central aperture to snugly receive the outer leg of said U-shaped portion, and means providing a shoulder upon which the head may seat, said U-shaped portion of the annulus when bent outwardly into a position substantially perpendicular to the core being adapted to clamp the head against said shoulder.

7. A spool having a core formed from a flat sheet of metal bent into tubular form, means forming a shoulder near the end of the core, a head in the form of a centrally apertured disk, said core having its end bent outwardly, and an annulus having a portion clamped directly between the head and said outwardly bent portion of the core and curled around the end of the core so as to extend a substantial distance into the core, said head being held against movement inwardly of the core by said shoulder.

8. In testimony whereof, I have hereunto affixed my signature.

WALLACE C. MILLS.
